DESIGN FOR A CARPET.

SPECIFICATION forming part of Design No. 20,759, dated May 19, 1891.

Application filed April 22, 1891. Serial No. 390,059. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of the body A and the border B. The body A consists of conventionalized flower bud and leaf forms, somewhat resembling the lotus, upon a shaded ground. The border B consists of conven-

tionalized flower leaf and bud forms, somewhat resembling the lotus, upon a shaded ground, of an irregular shaded inner margin, and an outer band-like margin of contrasted shading interspersed with outlined somewhat leaf-shaped forms.

What I claim, and desire to secure by Letters Patent, is—

1. The design for carpets, consisting of the body A, substantially as shown.
2. The design for carpets, consisting of the border B, substantially as shown.
3. The design for carpets, consisting of the body A and the border B, substantially as shown.
